UNITED STATES PATENT OFFICE

SYDNEY R. PATTERSON, OF DETROIT, MICHIGAN

CASKET HANDLE

Application filed May 20, 1929. Serial No. 364,410.

The present invention pertains to a novel means for attaching casket handles, particularly referring to caskets of the type which are expected to be hermetically sealed.

5 The primary object of the present invention is to overcome the problem arising from the difficulty of attaching the handles of metal caskets so that the latter may be hermetically sealed. It is the common practice to 10 drill holes in the casket and bolt the handles in place or by sweating or soldering a panel in place to accommodate the handle bolts. In both cases the body of the casket is cut or perforated and regardless of the use of 15 both cement and solder it is found by practice that after a period of time the solder or the cement give out and cause a leak.

A secondary object of the present invention is to provide a means for attaching handles to a hermetically sealed casket whereby the handles lie flush with the sides of the casket and are securely attached thereto without employing bolts or such means to pass through the walls of the casket.

25 With these and other objects in view my invention is fully set forth and more particularly pointed out in the appended claims, reference being had to the accompanying drawings, in which

30 Figure 1 is a horizontal cross-sectional view illustrating a portion of the casket wall with the handle mounted thereon;

Figure 2 is a fragmentary side elevation of the casket wall illustrating the handle mounting means;

Figure 3 is a horizontal cross sectional view illustrating a portion of the casket wall with a slightly modified mounting means;

Figure 4 is a transverse cross sectional view 40 on the line 4—4 of Figure 3, and

Figure 5 is a transverse cross sectional view illustrating a slightly modified holding means.

Like numerals of reference are employed 45 throughout to designate the corresponding parts.

The numeral 1 designates the side wall of the casket in which is drawn a recess or an indent 2 formed of the same material as the side wall such as by stamping, this being for

the purpose of allowing the handle to be seated flush with the side wall. The handle 3, illustrated in dotted lines in Figures 1 and 3, is pivotally mounted upon a base 4 which covers the recess or indent 2 and thereby covers the bolts and means employed for attaching the same, it being the object of this invention to secure this base to the casket wall without perforating or cutting the latter.

A plate 5 is electro-welded to the outside wall of the indent 2, the plate having extremities 6 which are flush with the outside wall of the casket and thereby permit the use of the nuts 7 without puncturing the casket walls. The nuts 7, as clearly illustrated in Figure 1, receive the ends of bolts 8 which are passed through the base 4 of the handle and thereby secure the latter to the handle.

It may be found desirable, however, to dispense with the nut 7 in which case the extremities 6 of the metal plate 5 are bent backwardly upon themselves as clearly indicated at 6' in Figs. 3 and 4. By bending the metal back upon itself in this manner a sufficient thickness of metal is provided whereby the bolts 8 may be threaded therethrough for securing the handle to the casket. Figure 4 illustrates the plate 5 having the extremities 6 to which are welded comparatively heavy strips of metal 9 to give sufficient material for the threads of the screws 8 to engage.

Although specific embodiments of my invention have been illustrated and described it is to be understood that various alterations may be made in the details of construction without departing from the spirit of the invention as depicted in the following claims.

What I claim is:—

1. The combination with a metal casket and handles having bases adapted to rest flush with the side walls of said casket, of means welded to the external faces of said side wall for attaching said bases to said side walls without perforating the latter, said means comprising plates received in indents whereby the outer faces of said plates do not project outwardly from said walls.

2. The combination with a metal casket and handles having bases adapted to rest flush

with the side wall of the casket, of indents formed in said side wall and adapted to be covered by said bases, and means external of said casket received in said indents to receive attaching members for securing said bases to said casket.

3. The combination with a hermetically sealed casket and handles having bases adapted to rest flush with the side wall of said casket, of indents formed in said side wall, and plates received in said indents, said plate providing means for attaching said bases to said side walls without perforating the latter.

4. The combination with a casket and handles having bases adapted to rest flush with the wall thereof, of indents formed in said wall, plates welded to the external face of the side wall of said casket in said indents whereby said plates do not project outwardly from the normal face of the wall, and screws passing through said handle bases into said plate whereby said handles are secured to said side wall without perforating the latter.

5. The combination with a casket and handles having bases adapted to rest flush with the side wall thereof, of indents formed in said wall, plates welded in said indents, and bent up portions on said plates, said bent portions adapted to receive securing means passed through said base whereby the handles may be secured to said wall to rest flush against the latter without perforating the same.

6. The combination with a metal casket and handles having bases adapted to rest flush with the side walls thereof, indents formed in said side walls, plates welded in said indents, bent up portions formed on said plates and adapted to rest flush with said side walls, and screws passed through said bases and received in said plates whereby said handles are secured to said walls without perforating the latter.

7. The combination with a hermetically sealed casket, of indents formed in the side walls thereof, plates secured in said indents, and bent up portions on said plates spaced from the walls of said indents and adapted to receive securing means for attaching handles to said casket.

8. The combination with a hermetically sealed metal casket, of indents formed in the side walls thereof, plates welded in said indents, and bent portions on said plates adapted to be disposed in spaced relation to the wall of each indent and adapted to receive securing means for attaching handles to said casket.

60 9. The combination with a hermetically sealed casket, of indents formed in the side walls thereof, plates secured in said indents, bent up portions on said plates spaced from the walls of said indents, handles having bases adapted to cover said indents, and se-

curing means passing through said bases into the bent up portion of said plates.

10. The combination with a hermetically sealed metal casket, of indents formed in the side walls thereof, plates welded in said indents, bent portions on said plates adapted to be disposed in spaced relation to the wall of each indent, handles having bases adapted to cover said indents, and securing means passing through said bases into the bent portion of said plate.

In testimony whereof I affix my signature.

SYDNEY R. PATTERSON.
